DESIGN FOR A DRESS

Samuel Bloom, Boston, Mass.

Application February 21, 1940, Serial No. 90,416

Term of patent 3½ years

To all whom it may concern:

Be it known that I, Samuel Bloom, a citizen of the United States of America, residing in Boston, county of Suffolk, and State of Massachusetts, have invented a new, original, and ornamental Design for a Dress, of which the following is a specification, reference being had to the accompanying drawing, forming part thereof, wherein,

I claim:

The ornamental design for a dress, substantially as shown.

SAMUEL BLOOM.
